GRILLE FOR RADIATORS

Filed Dec. 5, 1932

UNITED STATES PATENT OFFICE

1,991,506

GRILLE FOR RADIATORS

Homer G. Kellogg, Detroit, Mich., assignor to
 Motor Products Corporation, Detroit, Mich., a
 corporation of New York

Application December 5, 1932, Serial No. 645,849

7 Claims. (Cl. 293—54)

This invention relates to radiator grilles, and more particularly to grilles of the type now generally used in connection with the radiators of motor vehicles and the like.

5 One of the important objects of the invention is to provide a radiator grille of this type having means for spacing the louvers or louver blades with a readily attachable connection between the louvers and the said spacing means.

10 Heretofore, with structures of this type, when cross bars or other intermediate louver supports were employed, it was necessary to spot weld, or in some other permanent or semi-permanent manner, to attach the louvers to these cross bars or supports. In commercial production, this presented many obvious disadvantages.

15 It is therefore an object of this invention to eliminate this prior art practice and to provide cross bars or supports provided with means whereby the louvers may be readily attached thereto, as, for instance, by means of a snap-on engagement therewith.

The several objects, advantages, and novel details of this construction will be made more apparent as this description proceeds, especially when considered in connection with the accompanying drawing, wherein

20 Figure 1 is a front elevational view of a grille constructed in accordance with this invention;

25 Figure 2 is an enlarged fragmentary elevational view of the grille;

30 Figure 3 is a sectional view taken substantially on the plane indicated by line 3—3 in Figure 2;

35 Figure 4 is an enlarged sectional view taken substantially on the plane indicated by line 4—4 in Figure 2;

40 Figure 5 is an enlarged sectional view taken substantially on the plane indicated by line 5—5 in Figure 2;

45 Figure 6 is a fragmentary elevational view showing a slightly modified form of construction;

50 Figure 7 is a detail sectional view taken substantially on the plane indicated by line 7—7 in Figure 6;

55 Figure 8 is an enlarged detail sectional view similar to Figure 7, and

Figure 9 is a detail sectional view taken substantially on the plane indicated by line 9—9 in Figure 8.

Referring now particularly to the drawing and more especially to Figures 1 to 5 thereof, it will be noted that the grille comprises a frame 10 and louvers or louver blades 11. The reference character 12 indicates cross bars or supports for main-

taining the louvers in properly spaced relation intermediate the grille frame 10.

As shown most clearly in Figures 2 to 5 inclusive, the cross bars or supports 12 are each in the form of an inverted U-shaped channel member which may be conveniently formed by rolling. The side edges 13 of the channel member are return bent and are cut or shaped to form teeth 14. The teeth on the opposite sides thereof are undercut, as at 15, to form shoulder portions 16 with which the edges 17 of louvers or louver blades 18 are adapted to engage with a snap-on engagement.

The louver blades 18, in the form of invention herein illustrated, are in the form of substantially U-shaped channel members having the edges of the strip, constituting the extremities of the U, bent inwardly so that these louvers may be snapped onto the teeth 14 with the edges 17 thereof engaging the undercut portions 15 and 20 consequently the shoulders 16, it being understood that the louvers are preferably formed by rolling and are made of spring metal, or metal having some resiliency.

The head or extremity of each tooth 14 is 25 preferably rounded or curved, as shown at 19, to facilitate the engagement of the louver blades with the teeth.

It will be appreciated that by engagement of the spaced teeth 14 with the louver blades, relative angular movement of the louver blade is resisted and the engagement of the louver blade with the undercut portions and shoulder prevent accidental displacement or separation of the parts.

The cross bars or supports 12, as heretofore mentioned, may be conveniently formed by rolling, and the return bent edge portions 13 and the channel formation of the bar presents a stiff rigid support.

In Figures 6 to 9 inclusive, a slightly modified form of construction is illustrated in which the frame of the grille is indicated by the reference character 20 and the louvers by the reference character 21. The reference character 22 indicates a cross bar or support secured to the grille frame 20, as at 23.

In this form of the invention, the cross bar or support is in the form of a single bar provided with teeth 24 provided with undercut portions 25 providing shoulders with which the louver blade 26 is adapted to be connected by a snap-on engagement, as in the previously described construction.

In both forms of the invention, it will be obvious that the teeth may, in the production of the cross bars or supports, be properly spaced and arranged at the correct angle so that when the louvers are subsequently engaged therewith the louvers will not only be held properly spaced, but will be maintained at the desired angle, if the grille design demands such angular arrangement. The provision of the detachable snap-on connection between the louvers and supports enables the grille to be quickly assembled and the louvers accurately spaced, and eliminates the prior practices of welding or otherwise securing the louvers to the cross bars.

15 Obvious modifications may suggest themselves to those skilled in this art, and to this end reservation is made to make such changes as may come within the purview of the accompanying claims.

20 What I claim as my invention is:

1. In a radiator grille, a supporting bar having its longitudinal edges shaped to provide projections arranged in pairs spaced longitudinally of said bar, and a plurality of louver blades substantially U-shaped in cross section provided with means adapted for snap-on engagement with pairs of said projections of said supporting bar.

25 2. In a radiator grille, a supporting bar provided with a plurality of teeth-like projections having undercut portions near the base of the tooth providing shoulders, and a plurality of louver blades substantially U-shaped in cross section having the extremities of the U-shaped for snap-on engagement with said projections with the opposed edges of said louver blades engaging the undercut portions aforesaid of said projections.

30 3. In a radiator grille, a supporting bar substantially U-shaped in cross section with the longitudinal edges thereof return bent and shaped to provide longitudinally spaced pairs of tooth-like projections, and substantially U-shaped louver blades having the longitudinal edges there-

of shaped for snap-on engagement with the pairs of projections of said supporting bar.

4. In a grille assembly, a louver blade, a spacer bar, and cooperating means on said louver blade and spacer bar for frictionally securing said louver blade to said spacer bar, said cooperating means being designed to provide substantial contact with one another when assembled so that the frictional resistance to release said blade from the bar is greater than the frictional resistance to assembly of the blade and bar.

5 5. In a grille, a spacer bar having a plurality of longitudinally spaced projections shaped to form anchoring means, and a plurality of louver blades having integral portions thereof shaped for snap-on engagement with said anchoring means to secure said louver blades onto said spacer bar and provides substantial contact therebetween whereby the frictional resistance to release of the blades from the bar is greater than the frictional resistance to assembly of the blade and bar.

15 6. In a grille, a supporting bar having a plurality of pairs of longitudinally spaced projections, and a plurality of louver blades having portions adapted for snap-on engagement with the said pairs of projections to secure said louver blades to said supporting bar, said louver blades and projections being so shaped that when assembled they have substantial contact with one another whereby the resistance to disengagement of said blades and bar is greater than the resistance to assembly of the blades and bar.

20 7. In a grille, a supporting bar provided with a plurality of teeth-like projections having undercut portions providing shoulders, and a plurality of louver blades substantially U-shaped in cross section having the legs of the U-shaped for engagement with said projections with the opposed edges of said louver blades engaging the undercut portions aforesaid of said projections.

HOMER G. KELLOGG.
